UNITED STATES PATENT OFFICE.

JOHN ELMER RUTHERFORD, OF TORONTO, ONTARIO, CANADA.

DIRECTION INDICATOR FOR VEHICLES.

Application filed May 3, 1922. Serial No. 558,271.

To all whom it may concern:

Be it known that I, JOHN ELMER RUTHERFORD, of the city of Toronto, in the county of York, Province of Ontario, Canada, a subject of the King of Great Britain, have invented certain new and useful Improvements in Direction Indicators for Vehicles, of which the following is a specification.

This invention relates to devices used on motor cars to indicate the driver's intention to turn to the right or left or to stop. While numerous devices for this purpose have been invented, a large number of them are open to the objection that the signal is given by illuminating the same, and therefore cannot be used in daylight, or if used it is very difficult to distinguish the signal given. Another very common arrangement is to provide pointers of various kinds, which pointers are mechanically or electrically operated for giving the desired signals, most of which arrangements are awkward in operation or expensive to make.

My object is to devise a mechanically operated signal which will be effective in operation, compact in construction, which will give a sufficiently visible signal both during the day and night, which may be manufactured at a reasonable cost, and in which the signals will only be visible when it is desired to give an indication of the driver's intention.

Fig. 1 is a front view of the device;

Fig. 2 a vertical section of the same on a larger scale;

Fig. 3 a rear view of the lower part of

Fig. 2; and
Fig. 4 a horizontal section on the line
of Fig. 3.

40 In the drawings like numerals of reference indicate corresponding parts in the different figures.

1 is a casing, preferably of shallow oblong concave form, which is adapted to be secured to the rear of the vehicle in any convenient manner such, for example, as by the brackets 2. This casing will be formed of reflecting material or its inner surface given a suitable finish so that it will act as a light reflector.

Secured in front of the lower half of the casing 1 is a frame 3, which frame extends down below the lower edge of the casing and is provided with a rearwardly directed flange 12 extending partly under the casing.

93 Flange 12 extending partly under the casing.
Hinged on the upper side of the frame 3

is a door 4, which closes the upper part of the front of the casing, a suitable catch 5 being provided for holding the door closed.

Secured to the back of the door 4 and visible through a suitable opening in its face is the plate 6 having letters or numbers perforated therein to indicate the license designation of the car. The opening in the door 4 may be glazed, if desired, or the plate 6 may be dispensed with and the license numbers or letters may be applied directly to the transparency. 60 65

The frame 3 is preferably glazed, and behind the glass is placed a shield 8 having an opening formed at the centre thereof through which a "Stop" sign may be displayed, and an opening 7 adjacent each end preferably of arrow or other suitable shape for indicating "Right" or "Left." 75

In front of each opening 7 in the shield 8 is placed a slide 9, while behind the opening 7 at one side only of the shield 8 is placed a third slide 10 with the word "Stop" perforated therein. Each of the slides 9 and the slide 10 will be provided with a suitable lug 11 by means of which they may be operated. The lug on the slide 10 is so placed that when the slide 9 in front of it is operated the lug on the slide 9 will engage the lug on the slide 10 and simultaneously move the slide 10. 85

Behind the slide 10 and shield 8 is placed a screen 3 of a color contrasting with the color of the shield 8. 90

For operating the slides 9 and 10 I provide the following mechanism.

Supported on the end of the flange 12 remote from the stop slide 10 is a cage 19 in which are journalled two guide pulleys 13 and 14, while at the other end of the flange is supported a cage 20 in which is journalled a single guide pulley 15. Preferably the bolts used for securing the cages in place will also act as the journals for the guide pulleys. Round the guide pulley 13 passes a cable 16, which in practice may be connected at one end to the brake lever of the car and having its other end connected to the lug 11 on the stop slide 10. Round the guide pulley 14 passes a cable 17, which will be connected at one end to the slide 9 adjacent the stop slide 10, the other end of the cable being led to a position convenient for operation by the driver. Round the guide pulley 15 passes a cable 18, which at one end will be connected to the other slide 9,

and its other end led to a position convenient for operation by the driver. In practice these cables 17 and 18 may be led to the steering column of the car, where they may be provided with suitable grips for operation by the driver.

To return the slide 10 to normal position I mount on the cable 16, between the cage and the lug a compression coil spring 21, 10 the end of the spring bearing against the side of the cage, the latter being provided with suitable holes through which the cable passes. From this construction it will be seen that as the cable 16 is drawn upon to 15 operate, the slide 10, the spring is compressed, and immediately upon the release of the cable the spring returns the slide to normal position.

To return the slides 9 to normal position 20 I provide a single compression spring 24 through which the cables 17 and 18 pass, the ends of the spring bearing against the lugs on the slides 9. From this arrangement it follows that as either the cable 17 25 or 18 is drawn upon to move its respective slide 9, the spring is compressed against the lug on the opposite slide 9, which slide is therefore held firmly in a non-indicating position. When the cable is released the 30 slide which has been used is returned to non-indicating position. From this construction it will be seen that there is no possibility of both slides 9 being operated at the same time.

In the casing 1 immediately behind the central opening in the shield 8 is placed a lamp 22, and shining through said opening acts as the tail light for the vehicle.

In practice the shield 8 will be of a white 40 or other light color, while the colored screen 23 will be red.

The operation of the device is as follows. When the driver intends to stop the car, he will, of course, operate his brake pedal, 45 which draws upon the cable 16 to move the stop slide 10 behind the central opening in the shield 8 so that the word "Stop" is exposed. When the driver intends to turn to the right, he draws on the cable 17 50 to move the slide 9 to expose the arrow pointing to the right, and, at the same time, through the engagement of the lug on the slide 9 with the lug on the slide 10, the slide 10 is moved with the slide 9 so that

the slide 10 does not interfere with the exposing of the "Right" arrow. When the driver intends to turn to the left, he draws on the cable 18 to move the other slide 9 55 to expose the arrow pointing to the left.

As the cables are released the springs return the various slides to normal or non-indicating position.

If desired a similar device may be used 60 at the front of the car, but in this case it will not be necessary to provide the cen-

tral opening in the shield 8, nor to provide the stop slide 10, as it will only be necessary to give indication of the intention to turn to the right or left, it being understood that if no indication to turn is given that it is the intention to go straight ahead. This front signal, will, of course, be arranged to be operated simultaneously when the rear signal is operated.

When the lamp 22 is illuminated the usual 75 red tail light for the car will be displayed through the central opening in the shield 8, and the license number will always be illuminated.

With this arrangement the lamp 22 will 80 last considerably longer than is the case with numerous signals now known in which the lamps are being continually switched on and off to give the desired indications.

From the construction described it will 85 be seen that I have devised a construction which will satisfactorily attain the objects of my invention as set out in the preamble of this specification. It will be understood, of course, that I do not desire to limit myself to the particular arrangement shown of operating the various slides, as other arrangements for the same purpose might easily be devised.

What I claim as my invention is:— 95

1. In a vehicle signal, the combination of 100 an open fronted casing; a holder secured to the front of said casing; a shield having indication perforations therein; and slides in front of and normally concealing said 105 perforations but slidable within the casing relative to said shield to expose said perforations and means behind the shield illuminating the interior of the casing.

2. In a vehicle signal, the combination of 110 an open fronted casing; a holder secured to the front of said casing; a shield having an opening at its centre and an indication perforation at each end; a slide in front of and normally concealing one of said indication perforations; a slide in front of and 115 normally concealing the other indication perforation; a slide having an indication perforation therein mounted behind the shield and adapted to be exposed through the central opening in the shield; and means for moving any one of said slides to give an indication.

3. In a vehicle signal, the combination of 120 an open fronted casing; a holder secured to the front of said casing; a shield having an opening at its centre and an indication perforation at each end; a slide normally closing one of said indication perforations; a slide normally closing the other indication perforation; a slide having an indication perforation mounted therein behind the shield and adapted to be exposed through the central opening in the shield; and means for moving any one of said slides to give 125

an indication, said first mentioned slide being adapted when moved to engage and simultaneously move the last mentioned slide.

4. In a vehicle signal, the combination of an open fronted casing; a holder secured to the front of said casing; a shield having indication perforations therein; a transparent screen behind said shield, said shield and screen being of contrasting colors; slides in front of and normally concealing the said perforations but slideable relative to said shield to expose said screen; and means within the casing for illuminating the interior of the casing.

15 5. In a vehicle signal, the combination of an open fronted casing; a holder secured to the front of said casing; a shield having an opening at its centre and an indication perforation at each end; a slide normally closing one of said indication perforations; a slide normally closing the other indication perforation, each of said slides having a lug thereon; cables for actuating said slides to expose the indication perforations; and a compression spring mounted on said cables and engaging said lugs tending to keep the slides separated.

6. In a vehicle signal, the combination of an open fronted casing; a holder secured to the front of said casing; a shield having an opening at its centre and an indication perforation at each end; a slide normally closing one of said indication perforations; a slide normally closing the other indication perforation; a slide mounted behind the first mentioned slide, each of said slides having a lug thereon, the lug on the first mentioned slide when moved being adapted to engage the lug on the last mentioned slide to move the latter.

7. In a vehicle signal, the combination of an open fronted casing; a holder secured to the front of said casing; a shield having an opening at its centre and an indication perforation at each end; a slide normally closing one of said indication perforations; a slide normally closing the other indication perforation; a slide mounted behind the first mentioned slide; cables for actuating said slides to expose indication perforations; and a compression spring mounted on the cables for the first and second mentioned slides and engaging the lugs in said slides tending to keep the slides separated, each of the slides having a lug thereon, the lug on the first mentioned slide when moved

being adapted to engage the lug on the last mentioned slide to move the latter.

8. In a vehicle signal, the combination of an open fronted casing; a guide at one side of said casing; a guide parallel to the first mentioned guide but spaced from the opposite side of said casing; a shield having an indication therein adjacent each end and an opening at its centre and supported between said guides; a transparent screen behind said shield, said shield and screen being of contrasting colors; slides supported by said guides and movable in front of and normally concealing the perforations but slideable within the casing relative to said shield to expose the perforations; a sign plate between the second mentioned guide and the side of the casing; and means for illuminating the interior of the casing. 75

9. In a vehicle signal, the combination of an open fronted casing; a holder secured to the front of said casing; a shield having indication perforations therein; slides in front of and normally concealing said perforations but slideable within the casing relative to said shield to expose said perforations; a resilient member engaging both of said slides tending to hold each of them in non-indicating position; and means behind the shield for illuminating the interior of the casing. 80

10. In a vehicle signal, the combination of an open fronted casing; a holder secured to the front of said casing; a shield having an opening at its centre and an indication perforation at each end; and slides in front of and normally concealing said perforations but slideable within the casing relative to said shield to expose said perforations; and means behind the shield illuminating the interior of the casing. 85

11. In a vehicle signal, the combination of an open fronted casing; a holder secured to the front of said casing; a shield having an indication perforation at each end; a slide in front of and normally concealing one of said indication perforations; a second slide in front of and normally concealing the other indication perforation; a third slide having an indication perforation thereon mounted behind the first mentioned slide; and means for moving any one of said slides to give an indication. 100 105

Signed at Toronto Can. this 21st day of April 1922.

JOHN ELMER RUTHERFORD.
